TOBACCO CURING APPARATUS

Henry C. Sugg, Greenville, N. C.

Application May 11, 1937, Serial No. 142,052

1 Claim. (Cl. 34—19)

The present invention relates to new and useful improvements in means for curing tobacco and has for its primary object to provide, in a manner as hereinafter set forth, an apparatus of this character embodying a novel construction, combination and arrangement of parts through the medium of which a constant flow of fresh, heated air through the tobacco may be had.

Other objects of the invention are to provide a tobacco curing apparatus of the character described which will be comparatively simple in construction, strong, durable, highly efficient and reliable in use, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view principally in vertical longitudinal section through an embodiment of the apparatus.

Figure 2 is a view in horizontal section, taken substantially on the line 2—2 of Fig. 1.

Figure 3 is a cross sectional view, taken substantially on the line 3—3 of Fig. 1.

Figure 4 is a cross sectional view, taken substantially on the line 4—4 of Fig. 2.

Figure 5 is a view in vertical section through the upper portion of the ventilator.

Figure 6 is a horizontal sectional view, taken substantially on the line 6—6 of Fig. 1.

Figure 7 is a view principally in side elevation, showing a modification.

Referring now to the drawings in detail, it will be seen that the reference numeral 1 designates a tobacco barn of suitable dimensions having a peak roof 2. Installed in the barn 1, preferably adjacent one end thereof, is a furnace or other suitable heater 3 which is provided with an oil burner or coal stoker 4. A blower 5 is provided for the burner 4, said blower being located on the outside of the barn 1.

Extending horizontally adjacent the floor of the barn 1 and connected to the upper portion of the furnace 3 is a flue 6. Branches 7 are connected to the flue 6 and merge with an outlet 8 which passes through one of the walls of the barn 1.

Enclosing the furnace 3 are spaced inner and outer jackets 9 and 10, respectively. Communicating with the outer jacket 10 is a fresh air inlet conduit 11 which, as illustrated to advantage in Fig. 1 of the drawings, communicates with the

atmosphere through the end of the barn 1 which is remote from the furnace 3. The conduit 11 is provided with an enlarged intake end portion 12 having mounted therein a blower 13.

Communicating with the inner jacket 9 is a discharge or return conduit 14 which extends horizontally below the conduit 11 in parallelism therewith. Also, the conduit 14 extends above the flue 6 in parallelism therewith. Communicating with the conduit 14 are branches 15 having upturned free end portions 16 on which spreaders 17 are mounted. A damper 18 is provided in the conduit 14 adjacent the inner jacket 9. The reference numeral 19 designates a damper in the conduit 11. At a point diametrically opposite the conduits 11 and 14, the inner jacket 9 communicates with the outer jacket 10 through an opening 20. Any suitable means may be provided to permit access to be had to the burner 4.

Mounted longitudinally beneath the roof 2 of the barn 1 is a ventilating conduit 21 having connected thereto oppositely inclined intake branches 22. The ventilating conduit 21 is further provided, at an intermediate point, with an upstanding outlet 23 which extends through the roof 2 and which is provided with a damper 24.

It is thought that the operation of the invention will be readily apparent from a consideration of the foregoing. The tobacco to be cured is hung in the usual manner at the desired elevation above the floor of the barn 1. With the burner 4 in operation, fresh air from the atmosphere is blown through the conduit 11 into the outer jacket 10 and in this manner said air is pre-heated. This air then enters the inner jacket 9 through the opening 20 where it is brought to the desired temperature and from which it enters the conduit 14. This heated air is then distributed substantially evenly in the lower portion of the barn 1 through the discharge branches 15. 30 35 40 45 50

36 is a damper in branches 15 used in securing an even temperature in the barn 1. After being discharged from the branches 15 the heated air flows upwardly through the tobacco into the ventilating conduit 21 from which it is returned to the atmosphere through the outlet 23. As the conduit 11 is located immediately above the conduit 14, the temperature of the incoming fresh air will be raised before it enters the outer jacket 10. Also, the conduit 11 functions as a guard to prevent inflammable matter from falling on the hot air conduit 14. The construction and arrangement of the flue 6 and the branches 7 thereof is such that the heat from the exhausting products of combustion from the furnace 3 will be 55

utilized to assist in warming the interior of the barn 1. Of course, the flow of air may be conveniently controlled as desired through the medium of the dampers 18, 19 and 26. It will 5 thus be seen that an apparatus has been provided whereby a constant flow of fresh, warm air through the suspended tobacco in the barn 1 will be had.

In the modification shown in Fig. 7 of the drawings, the reference numeral 25 designates an elongated furnace of brick or other suitable construction in which a suitable burner is provided. A flue 26 is connected to one end of the furnace 25. Mounted on the furnace 25 is an elongated 15 casing 27 of suitable metal having mounted longitudinally therein a horizontal partition 28 providing intake and discharge passages 29 and 30, respectively. The intake passage 29 is provided with an enlarged, longitudinally projecting intake 20 end portion 30. The partition 28 is spaced from one of the end walls of the casing 27, as at 31, to permit the air to enter the discharge passage 30 from the intake passage 29. Extending horizontally in opposite directions from the discharge 25 passage 30 are branches 32 having upturned free end portions 33 provided with spreaders 34. A blower 35 is provided in the enlarged intake end 30 of the passage 29.

In operation, fresh air from the atmosphere enters the passage 29 of the casing 27 through the enlarged intake end portion 30 of said passage 29 and is preheated. This air then flows back

through the passage 30 where it is brought to the desired temperature and from which it is discharged into the barn through the branches 33. In addition to curing tobacco, the apparatus may also be used for drying fruits and vegetables. 6

It is believed that the many advantages of a tobacco curing apparatus constructed in accordance with the present invention will be readily understood and although preferred embodiments of the invention are as illustrated and described, 10 it is to be understood that further modifications and changes in the details of construction may be resorted to which will fall within the scope of the invention as claimed.

What is claimed is:— 15

In a drying chamber, a horizontally arranged inlet pipe having one end in communication with the atmosphere, heating means for heating the air leaving said pipe, an outlet pipe for the heated air paralleling the first pipe and located under 20 the same, branch pipes leading from the outlet pipe and having their outer ends extending upwardly, dampers in the branch pipes for controlling the flow of heated air therethrough, hoods covering the upper ends of said upwardly extending portions of the branch pipes for distributing the heated air through the chamber, an outlet pipe leading from the top of the chamber, pipes extending along the top of the chamber and leading into the outlet pipe. 25
